(57) **CLAIM**

The design for a wireless power transmission apparatus of portable electronic device, as shown and described.

DESCRIPTION

FIG. 1 is a perspective view of the wireless power transmission apparatus of the portable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawing views are included to show unclaimed environment only and form no part of the claimed design.

The present design is used for transmitting a wireless power signal to the portable electronic device such as a smart phone and laptop computer.
